UNITED STATES PATENT OFFICE.

JOHN K. DEEM, OF RICHMOND, INDIANA.

VARIABLE-EXHAUST CONTROL.

1,110,046.

Specification of Letters Patent.

Patented Sept. 8, 1914.

Application filed December 14, 1912. Serial No. 736,794.

To all whom it may concern:

Be it known that I, JOHN K. DEEM, a citizen of the United States, residing at Richmond, in the county of Wayne and State of Indiana, have invented certain new and useful Improvements in Variable Exhaust Control, of which the following is a specification, reference being had therein to the accompanying drawing.

10 This invention relates to means for controlling the draft of the exhaust through the fire box in the furnace of a locomotive, and has for its object the production of an efficient adjusting means whereby the exhaust 15 opening may be enlarged or reduced to control the passage of the exhaust steam there-through.

Another object of this invention is the production of an efficient cap carried by the 20 exhaust stand which may be adjusted for reducing the discharge opening through which the exhaust steam is adapted to be discharged.

With these and other objects in view, this 25 invention consists of certain novel constructions, combinations and arrangements of parts, as will be hereinafter fully described and claimed.

In the drawings:—Figure 1 is a fragmentary side elevation of a locomotive. Fig. 2 is an enlarged vertical section of the adjusting cap for the exhaust stand. Fig. 3 is a side elevation of the cap detached from the exhaust stand. Fig. 4 is a fragmentary 35 side elevation of the inner closure sections of the exhaust stand.

By referring to the drawings by numerals it will be seen that the locomotive is provided with the usual exhaust stand 1, and 40 upon the upper end of this exhaust stand is placed the collapsible cap 2. This collapsible cap 2 comprises an inner series of closure sections 3 and an outer series of closure sections 4. The inner series of closure sections 45 have their lower ends secured to the securing band 5 by means of rivets 6 which rivets pass through the semicircular notches 7 formed along the side edges of the collapsible sections 3. Each of these collapsible sections 50 comprises enlarged base portions tapering toward their upper ends so as to allow the sections to be brought together near their upper ends and reduce the discharge opening. The outer series of closure sections are 55 placed over the top of the inner series of closure sections 3 as illustrated in Fig. 2 so

as to straddle the junction portion of the sections of the inner series 3. The securing rivets 6 also pass through the apertures 8 formed in the base of the sections of the outer series 4 and these series of sections 3 and 4 will thereby be firmly held together. Rivets 9 pass through the outer series of sections 4 and the inner series 3 as illustrated in Fig. 2 for firmly holding the sections 3 and 4 upon the upper end of the exhaust stand 1. A plurality of these rivets 9 secure the series 3 and 4 of the closure sections to the stand 1 for constituting a secure fastening means therefor. These rivets 9 also pass through the band 5 as illustrated in Fig. 2. 60

The upper ends of the series of closure sections 3 and 4 are left free and a conical hood 10 fits over the upper end of these sections and is adapted to close the same as the 70 hood 10 is drawn down longitudinally of the sections 3 and 4. This conical hood is provided with a plurality of depending arms 11 which arms are connected to the crank lever 12, said crank lever being mounted upon an 75 operating shaft 13. A crank arm 14 is connected to the outer end of this shaft 13 and this crank arm 14 is connected to the operating lever 15 by means of the link connection 16 as illustrated in Fig. 1 so as to allow 80 the hood 10 to be operated upon the collapsible or closure sections carried by the upper end of the exhaust stand 1. The outer ends of the crank arms 12 are slotted as indicated at 17 to allow the free movement of the 85 cranks 12 relative to the depending arms 11. This shaft 13 is suspended from the body 90 of the locomotive. Each section of the series 3 and 4 of the closure sections is formed preferably of metal one-quarter of an inch 95 in thickness and it will, therefore, be seen that when the conical hood 10 is drawn down closely over the closure sections to the position shown in full lines in Fig. 2, the opening made by the top of the closure sections will be one inch smaller than the opening in the upper end of the conical hood 10. This will materially reduce the size of the discharge opening thereby reducing the draft 100 through the exhaust stand. It, of course, 105 should be understood that these closure sections may be made of spring metal if so desired, but the force of the exhaust through the exhaust stand will be of sufficient strength as to normally hold these closure sections in 110 an expanded condition relative to the exhaust stand as there will be a constant out-

ward pressure upon the upper ends of the closure sections when the hood 10 is released therefrom.

From the foregoing description it will be seen that a very efficient and durable device has been shown which will be very efficiently and easily operated so as to control the draft through the fire box of an engine by means of the adjustable hood 10 placed upon the upper end of the exhaust stand.

It should be noted that the present device is especially adapted to be used in connection with a locomotive and especially where 15 locomotives are employed in the country where considerable grades occur along the road bed. When it is desired to obtain a strong draft through the fire box the expandible cap is contracted so as to increase 20 the draft through the upper end of the exhaust stand but as soon as the locomotive or train has reached a flat stretch of road the hood may be operated to permit the cap to expand and reduce the draft, thereby saving 25 considerable fuel in the operation of the engine.

The exhaust stand is placed directly under the stack of the locomotive as is illustrated clearly in Fig. 1, and in view of this fact 30 will efficiently control the draft through the stack of the locomotive. This control is made possible for the reason that the exhaust steam will be discharged through the exhaust stand so as to force the steam 35 through the stack of the locomotive and in this manner create a draft therethrough, and at the same time create a draft through the fire-box.

Having thus described the invention, 40 what is claimed as new, is:—

1. In a locomotive provided with a fire-box, a stack carried by said locomotive, of an exhaust control comprising a stand placed below said stack, a cap formed of

flexible sections, a band, said flexible sections fixedly secured to said band and capable of being drawn together to constitute a substantially dome-like housing, a funnel slidably mounted over said flexible sections and adapted to move vertically 45 thereof and also adapted to draw the upper ends of said sections closely together and constitute means for regulating the size of the discharge opening of said stand, said flexible sections being arranged in an inner 50 and outer tier, said outer tier of sections fitting over the joint of the several sections between the inner tier of sections, thereby constituting a yieldable and smoke tight casing for preventing the escape of smoke 55 or gas through the sides of the casing and at the same time constituting means for allowing a free lateral expansion and a free contraction of said sections for controlling the discharge of steam from said stand 60 through said stack, and means for moving said slidably mounted funnel vertically for regulating the distance between the discharge opening of said stand and the lower 65 end of said stack.

2. In a locomotive provided with a fire-box, a stack carried by said locomotive, of a stand positioned below said stack, collapsible means carried by said stand for increasing and decreasing the size of the discharge 70 opening of said stand, a vertical movable funnel fitting over said collapsible means, and means for moving said funnel vertically for decreasing the distance between said discharge opening of said stand and the 75 lower opening of said stack.

In testimony whereof I hereunto affix my signature in presence of two witnesses.

JOHN K. DEEM.
